(57) **CLAIM**

The ornamental design for a lanyard for controller as shown and described.

DESCRIPTION

FIG. 1 is a perspective view of front, top and left side of a lanyard for controller showing my new design;
FIG. 2 is a perspective view of rear, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a reference view of usage thereof.

The broken lines shown in FIG. 9 depict environment and form no part of the claimed design.

1 Claim, 6 Drawing Sheets
